DRAFT REGULATOR

Thomas J. Colihan, Girardville, Pa.

Application November 19, 1937, Serial No. 175,525

1 Claim. (Cl. 236—45)

My invention relates to improvements in draft regulators for use on boilers, more particularly locomotive boilers.

The invention is designed with the particular purpose in view of providing a practical, inexpensive means of simple construction adapted to be readily attached to the smoke box of a locomotive for operation under the blast of the exhaust passing therethrough to break the pull, or lift, in the fire box incident to the rush of the exhaust through the smoke box, and thereby obviate undue suction in said fire box such as would tend to draw flames and sparks therefrom through the boiler flues.

15 To the accomplishment of the above, and subordinate objects presently appearing, a preferred embodiment of my invention has been illustrated in the accompanying drawings, set forth in detail in the succeeding description, and defined in the 20 claim appended hereto.

In said drawings—

Figure 1 is a fragmentary view in vertical longitudinal section of a locomotive boiler having my improved draft regulator applied thereto.

25 Figure 2 is a view in front elevation,

Figure 3 is a view in vertical transverse section taken on the line 3—3 of Figure 1 looking in the direction indicated by the arrows, and

Figure 4 is a view in perspective of a bracket forming part of the device.

30 Referring to the drawings by numerals, my invention has been shown therein as applied to a locomotive boiler 1 including the usual flues 2, front flue plate 3, smoke box 4 having the front plate 5, smoke stack 6 and the usual exhaust pipe 7 leading from the cylinders, not shown, into the smoke box 4.

According to my invention, a circular aperture 8, of any suitable size, is provided in the front plate 5 axially thereof and for the admission of atmospheric air into the fire box 4. A U-shaped bracket 9, of right angles form and of suitable metal, and comprising a breast bar 10 and right angled legs 11 is secured to the plate 5 in upright position, in the center of the aperture 8, by means of bolts 12 extending through said legs and plates and having nuts 13 threaded on to the ends thereof. Extending inwardly, equidistantly from the breast bar 10 through said aperture 8 and into the smoke box 4, for a suitable distance, is a pair of upper and lower, horizontally disposed guide rods 14 and 15, each secured at its front end in said breast bar 10 by means of a pair of nuts 16 threaded thereon upon opposite sides of said bar 10 respectively. The guide rods 14 and 15 are each provided on their inner ends with a head 17. Slidably mounted on the guide rods 14 and 15, on the inner side of

the aperture 8, is a circular closure plate 18 of sufficient diameter to close said aperture. Preferably the plate 18 has formed thereon guide sleeves 19 through which the rods 14 and 15 extend and which prevent said plate from binding 5 on said rods. The plate 18 is yieldingly urged against the inner side of the front plate 5, in closing position, by means of a tension spring 20 having its opposite ends secured to a pair of eye bolts 21 and 22 secured in the center of the plate 10 and said breast bar 10, respectively, as by nuts 23.

As will now be seen the device described forms a valve in which the closure plate 18 is the valve member tensioned by the spring 20 to seat 15 against the front plate 5 and close the valve opening 8 and so that when the exhaust steam blasts through the smoke box 4 the suction created therein by the blast will pull the plate 18, or valve member, into opening position in opposition to the spring 20 and admit air to the smoke box 4. As will be understood the air thus admitted to the smoke box 4 will break the suction created in the fire box, by way of the flues 2, under such action of the exhaust steam, and thereby obviate the discharge of 25 sparks from the smoke stack 6 also the formation of holes in the fire bed. The heads 17 on the rods 14 and 15, as will be manifest, establish the limit of opening movement of the plate 18, or 30 valve member, as shown by dotted lines in Figure 1.

The invention will, it is believed, be readily understood from the foregoing without further explanation.

35 Manifestly, modifications in structural features described may be resorted to without departing from the inventive concept and right is herein reserved to all such modifications falling within the scope of the subjoined claim.

40 What I claim is:

A draft regulator for use on a boiler smoke box of the type having a draft opening therein, said regulator comprising a U-shaped bracket adapted to be secured to the outer side of said 45 box and to span said opening, a pair of guide rods extending from said bracket and adapted to extend through said opening into said box, a closure plate slidably mounted on said rods and adapted to be disposed in said box for movement 50 on the rods into and from closing relation to said opening, a tension spring connected at its opposite ends to said plate and bracket to urge said plate toward closing relation, and stops on said rods for limiting movement of the plate thereon 55 from closing relation.

THOMAS J. COLIHAN.
